Primary Examiner — Philip S Hyder*Assistant Examiner* — Roselynne Cody(74) *Attorney, Agent, or Firm* — TraskBritt(57) **CLAIM**

The ornamental design for a prybar, as shown and described.

DESCRIPTION

FIG. 1 is a perspective view of an embodiment of a prybar; FIG. 2 is a left side view of the prybar shown in FIG. 1; FIG. 3 is a right side view of the prybar shown in FIG. 1; FIG. 4 is a top view of the prybar shown in FIG. 1; FIG. 5 is a bottom view of the prybar shown in FIG. 1; FIG. 6 is a front view of the prybar shown in FIG. 1; and, FIG. 7 is a rear view of the prybar shown in FIG. 1. The broken lines in the drawings illustrate a portion of the prybar that forms no part of the claim.

1 Claim, 3 Drawing Sheets(56)
